FIG. 1

FIG. 2

FIG. 3

FIG. 4.

FIG. 1 is a front elevational view of an escutcheon plate for a bathroom fixture or the like embodying our new design;

FIG. 2 is a side perspective view thereof;

FIG. 3 is a front perspective view thereof; and

FIG. 4 is an enlarged front elevational view showing details of one full segment of the pattern that is repeated circumferentially on the face of the escutcheon plate, and the radial broken lines indicate where each repeat of the pattern begins.

The broken line representation of a bracket and dish in FIG. 3 is for purposes of illustration only.

We claim:

The ornamental design for an escutcheon plate for a bathroom fixture or the like, as shown and described.
